UNITED STATES PATENT OFFICE.

VITO GLISCI, OF WATERBURY, CONNECTICUT.

AUTOMATIC DISPENSING WATER COOLER.

1,407,264.

Specification of Letters Patent. Patented Feb. 21, 1922.

Application filed August 13, 1920. Serial No. 403,189.

To all whom it may concern:

Be it known that I, VITO GLISCI, a subject of the King of Italy, and a resident of Waterbury, in the county of New Haven 5 and State of Connecticut, have invented certain new and useful Improvements in Automatic Dispensing Water Coolers, which improvements are fully set forth in the following specification.

10 This invention relates to improvements in apparatus of that class available for maintaining a supply of cooled water and for automatically replenishing any volume thereof which may be drawn therefrom, as 15 for drinking or other purposes, such apparatus being well designated Automatic dispensing water-coolers.

The object of this invention is to provide 20 a water-cooler of the character above indicated, which shall be comparatively simple and inexpensive as regards its construction; durable, efficient and reliable in practical service; convenient in its application to 25 practical purposes; and which shall possess certain well-defined advantages over prior analogous constructions.

The invention consists in the combinations, details and parts hereinafter more particularly referred to and set forth in the 30 appended claims, and whereby the attainment of the foregoing object is rendered practicable.

The invention is clearly illustrated in the accompanying drawing, wherein:

35 Fig. 1 is a view mainly in top plan of an automatic water-cooler embodying my said improvements, the cover of the main housing being swung upwardly and backwardly to a position approximately horizontal, the cover of the interior storage tank being swung upwardly to a position approximately vertical, and the air-agitating 40 compartment being shown partly in central, horizontal section, as along the dotted line 45 1—1 of Fig. 2.

Fig. 2 is a front elevation of same, the end-wall of the air-agitating compartment being partially removed.

Fig. 3 is a rear end elevation of the air- 50 agitating compartment detached, the end-wall thereof being partially removed.

Fig. 4 is a central, vertical, longitudinal section, as along the dotted line 4—4 of Fig. 1.

55 Fig. 5 is a view showing in side elevation the general storage section of my im-

proved cooler, the near walls of the main housing and the interior storage tank being broken away.

Fig. 6 is a vertical transverse section, as 60 along the dotted line 6—6 of Fig. 5.

Fig. 7 is a side elevation of the air-agitating compartment, detached.

Fig. 8 is a view showing detached and in perspective the pebble tray made use of. 65

Similar reference-numerals denote like parts throughout the several views of the drawings; and in carrying out my present invention I make use of a general housing 2, fitted with a cover 2', and wherein is 70 positioned a storage tank 3, fitted with a cover 3'.

There is, in turn, positioned within the storage tank 3 a tray 3'', best supported by opposite legs 4', 4'', 5', 5'', a float-housing 4 being, in turn, displaceably supported by said tray, fitted with a suitable door 5, by way of which access to the interior of the float-housing may be had, and having arranged therein a primary distributing 80 compartment 6, fitted with an intake 6' and an outlet 6'', the latter controlled by a valve 7, attached to the stem 7' of a float 7'', and operating as a unit therewith.

The tray 3'' has disposed thereon a mass 85 or volume of pebbles 8'.

An air-space 8 jackets the storage tank 3 and a similar space for air and water circulation jackets the float-housing 4.

8'' denotes a water intake-pipe, attachable 90 at its intake end, to, say, a faucet, or other unit of a circulation system affording a general supply of drinkable water under pressure, and leading inwardly through the general housing aforesigned, and the storage 95 tank aforesigned, and having its delivery end arranged in communication with the intake 6', a branch pipe 9', controllable exteriorly of the general housing aforesigned, as by means of a hand-operable valve 9'', 100 leading therefrom substantially as shown and for a purpose to be hereinafter more fully explained.

The storage tank 3 is provided with a draw-off faucet 10, whose shank intersects 105 and traverses, in this instance, the space 8; and a suitably disposed thermometer 10', may also be provided, whereby the temperature of the interior, say, of the general housing aforesigned, and incidentally the 110 contents of the tank 3, may be indicated to the user of my improved cooler, and pref-

erably at the exterior of said general housing.

Any suitable medium, as the upstanding yoke 9, may be employed for guiding in its 5 operation the valve-affording float of my improved cooler.

10" denotes an air-agitating compartment arranged fixedly in close relation to the general housing 2, at one side thereof; 10 and within the casing forming said air-agitating compartment there is snugly disposed a transverse partition 11", whereby is formed, adjacent said air-agitating compartment, a propeller chamber 12.

15 Within said air agitating compartment, and traversing the propeller chamber, there is mounted to rotate an air agitator, which includes in this instance an operating shaft 11, fitted within the air-agitating compartment with air-agitating blades 11', and within the propeller chamber with a propeller 11", the latter mounted on and rotatable as a unit with, the operating shaft 20 aforesaid under a flow of water duly applied thereto, and whereby the agitating blades aforesaid are correspondingly rotated for an air-agitating effect on the air contained within said air-agitating compartment.

30 Communication for air-circulation is established between the air-agitating compartment aforesaid and the interior of the storage tank 3 by way of suitable intermediate air-ducts as 12', and, when desired or 35 deemed needful, between said air-agitating compartment and the interior of the general housing 2, by way of similar air-ducts 12", the air-agitating blades carried by the shaft 11 being so shaped and so applied to said 40 shaft as to draw outside air into the air-agitating compartment, as by way of a suitable opening 13 formed, say, in the end-wall of the latter, agitate the same, and force the same, said shaft being duly turned, into the 45 interior of said storage tank and the interior of said general housing, respectively, by way of said intermediate air-ducts, respectively.

Any appropriate bearings may be provided for the shaft 11, as the socket 13' for 50 one end thereof, and the coil 13" of the arm 14, for the opposite end thereof, said arm disposed diametrically and fixedly within the air-agitating compartment; and to avoid the accumulation of any volume of water 55 within the agitating compartment, as from the propeller chamber 12, and due, say, to leakage at the partition 11", said air-agitating compartment is provided with a drain pipe 14', here shown as arranged to deliver 60 any volume of water finding its way therein to and into the general outlet 14", with which the propeller chamber 12 is provided.

15 is a delivery terminal connected to the branch pipe 9' at the delivery end thereof, 65 leading therefrom to and into the propeller

chamber 12, and terminating at its delivery end adjacent the propeller 11", and in a manner to incessantly deliver a flow of water under pressure to and against the propeller aforesaid for actuating the same, and 70 hence the shaft 11 with the blades carried thereby, the hand-valve 9" being open.

In operation, my improved cooler being duly positioned for service with its main intake 8" arranged in connection, as through 75 the medium of a suitable valve-controlled union 15' with a source of water under pressure, and in a manner to duly care for and conduct away, as through the medium of a customary waste-pipe, the outflow from its 80 general outlet 14", a flow of such water under pressure is let into the main intake 8", such water then finding its way, in part into the primary distributing compartment 6, and from thence to and into the storage tank 85 3, until the level thereof shall rise sufficiently to cause, through the medium of the float 7", the closure of the outlet 6" of said primary distributing compartment, by the valve 7; and in part, by way of the branch 90 pipe 9', to and into the propeller chamber 12, for actuating the propeller 11" as hereinbefore explained, the air thus agitated, through the action of the blades 11', and accordingly brought to a relatively low temperature, being conducted to and into the interior, more essentially of the storage tank 3, and incidentally to and into the interior of the general housing 2, for air-jacketing purposes, and whereby a marked cooling effect 100 is had on the water contained in said storage tank.

It will be observed that upon any volume of the contents of tank 3 being withdrawn therefrom, as by means of the faucet 10, thus 105 lowering the level of such contents, float 7" will descend accordingly, thereby causing its stem to rock correspondingly within the yoke 9, and hence open the valve 7, thereby permitting replenishment of the volume of 110 water drawn off as stated and a restoration, automatically, of the level of the contents of tank 3, float 9 being accordingly lifted and valve 7 accordingly closed, until a further volume of the contents of tank 3 115 shall be withdrawn therefrom and correspondingly replenished.

It will be further observed that my improved cooler is not only automatic in its 120 replenishment of any volume of the contents of tank 3 which may be withdrawn therefrom, but in its driving of the shaft 11, and hence the furnishing of a supply of cooled air for cooling the contents of said tank, this being all accomplished with a 125 single volume of water originally inflowing under pressure by way of the main intake 8" and thereafter divided for the purposes stated.

When conditions do not make needful or 130

desirable the cooling of the contents of tank 3, as during the winter season, the flow of water for actuating the propeller 11" may be readily cut off by means of the hand-valve 9".

The device is portable and may be readily shifted from place to place, as occasion may make desirable.

My improved cooler is particularly well 10 adapted for the purposes for which it is intended, and is well calculated to effect marked economy in the use of ice.

The operation of my improved cooler should be apparent from the foregoing description thereof, and it will be noted that the same may be modified, particularly as regards the specific character of the air-agitating medium made use of, the arrangement of the air and of the water circulation 15 system availed of, and various minor details of the general construction, without materially departing from the spirit and principle of my invention as set forth in and coming within the scope of the claims 20 hereto appended.

Having thus described my invention, I claim:

1. A water-cooler comprising a main housing; a storage tank positioned within 30 said housing and surrounded in the main by a substantial jacketing-space; a float housing displaceably seated within said storage tank and including a closed primary distributing compartment having at its top an inlet and an outlet, the latter fitted with a valve-seat; a rocking stem; fitted with a valve at one end thereof; a float within said float-housing and coacting with said stem at the opposite end thereof, whereby control of 35 the outlet aforesaid under variations in the level of the contents of said tank, and through the medium of the valve aforesaid, is effected; an intake pipe whereby is conducted a constant supply of drinkable 40 water to and into said distributing compartment by way of the inlet thereof; and a draw-off faucet, the latter operable exteriorly of the said main housing and whereby may be withdrawn the contents of the 45 storage tank aforesaid.

2. A water-cooler comprising a main housing; a storage tank positioned within 50 said housing; a tray fitted with supporting legs displaceably positioned within said tank and supporting a mass of pebbles; a float-housing displaceably seated on said

tray and including a closed primary distributing compartment having at its top an inlet and an outlet, the latter fitted with a valve-seat; a valve co-acting with said outlet; a float within said float-housing; a connection between said float and said valve whereby the latter is caused to control the outlet aforesaid under variations in the level of the contents of said tank; an intake 60 pipe whereby is conducted a constant supply of drinkable water to and into said distributing compartment by way of the inlet thereof; and a draw-off faucet, the latter operable exteriorly of the main housing and whereby may be withdrawn the contents of the storage tank aforesaid.

3. A water-cooler comprising a main housing; a storage tank positioned within 65 said housing and provided with a cover at its top; a float-housing displaceably seated within said tank, provided with a door at one side thereof, and including a closed primary distributing compartment having at its top an uncontrolled inlet and a valve-controlled outlet; a float within said float-housing and capable of actuating, through 70 variations in the level of the contents of said tank, the valve controlling said outlet, said float-housing and distributing compartment being insertible into and removable from said tank as a unit; an intake pipe 75 whereby is conducted a constant supply of drinkable water to and into said distributing compartment by way of the inlet thereof; and a draw-off faucet, the latter operable exteriorly of the main housing and whereby may be withdrawn the contents of the storage tank aforesaid.

4. A water cooler comprising a storage 80 tank fitted with a cover at its top; a float-housing, including a primary distributing compartment having at its top an inlet and a valve-controlled outlet, said float-housing and distributing compartment insertible into 85 and removable from said tank as a unit; a float within said float-housing and capable of actuating, through variations in the level of the contents of said tank, the valve controlling said outlet; a draw-off faucet 90 whereby may be withdrawn the contents of said storage tank.

VITO GLISCI.
